LIFTING JACK

Application filed April 21, 1924. Serial No. 707,815.

This invention relates to improvements in lifting jacks and its purpose is to provide a simplified and improved jack for use in lifting automobiles or other objects.

The principal object of the invention is to provide a jack of great simplicity, the frame or standard of which may be stamped from sheet steel or the like. Another important object is to provide improved operating mechanism for raising and lowering the plunger or supporting member of the jack. Another object is to provide a jack comprising a rack bar adapted to be raised and lowered by a pivoted lever which carries a pawl and a detent connected by a spring which is adapted to move them out of engagement with the rack bar intermittently during the operation of the lever for lowering the rack, another spring being adapted to be moved into engagement with the pawl and the detent and to overcome the first named spring for forcing the pawl and detent into engagement with the rack during the operation of the lever for elevating the rack or plunger. Other objects relate to various features of construction and arrangement which will appear more clearly hereinafter.

The nature of the invention will be understood from the following specification taken with the accompanying drawings in which one embodiment is illustrated. In the drawings Figure 1 shows a vertical section through the improved jack, illustrating a side elevation of the operating mechanism for raising or lowering the rack bar or plunger; Fig. 2 shows a horizontal section taken on the line 2-2 of Fig. 1; Fig. 3 is a view similar to Fig. 2 showing a partial side elevation of the operating mechanism with the lever elevated and one of the controlling springs rendered inoperative to permit the lowering of the rack or plunger; Fig. 4 is a view similar to Fig. 3 showing the position of the parts when the lever is in its lower position; Fig. 5 shows a side elevation of the end of the lever and the pawl and detent with their springs removed from the standard or casing of the jack; Fig. 6 shows a detail section taken on the line 6-6 of

Fig. 5; and Fig. 7 is a view similar to Fig. 5, showing a modification.

The frame or supporting structure of the jack may be readily formed at small cost by stamping the principal parts thereof from sheet steel or the like. This structure comprises a base 10, of rectangular form having an annular depending flange 10^a adapted to rest on the support for the jacket. The base 10 forms a support for a vertical standard 60 or casing 11 which, like the part 10, is stamped from sheet steel or the like in one piece. The part 11 comprises two side walls 11^a which are provided at their lower ends with transversely extending flanges 11^b secured to the base 10 by means of rivets 12. The vertical side walls 11^a of the standard are connected by a single integral end wall 11^c. The side walls 11^a are provided with inclined edges 11^d at their upper ends and an inclined top wall or cover 13 extends between these inclined edges with the ends thereof rolled to form cylindrical parts 13^a adapted to be engaged by the rivets 14 which extend between the side walls 11^a. The opening is 75 thus formed between the top wall 13 and the end wall 11^c to receive the vertical plunger or rack bar 15 of the jack. This plunger is provided along one edge with rack teeth 15^a and it is prevented from accidental removal 80 from the casing or standard 11 by a transverse pin 16 which extends through an aperture in the lower part thereof with its ends loosely engaging the grooves 17 which are formed in the side walls 11^a and which are 85 closed at their upper and lower ends. In assembling the jack, the pin 16 is put in place in the plunger 15 after which the side walls 11^a are bent into parallel relation to secure the rack bar in position before the 90 standard 11 is attached to the base. The rack bar 15 is provided at its upper end with a saddle 15^b mounted on a vertical pivot 15^c and adapted to engage the axle of the automobile or a suitable part of any other object 95 to be raised.

The plunger or rack bar of the jack is raised and lowered by the reciprocation of a lever 20 which extends between the side walls 11^a and is pivoted on a transverse pin or 100

axle 21 extending through these side walls. The lever 20 may be formed in two parts including a handle portion 20^a of suitable length and a sheet metal part 20^b which is 5 engaged by the pin 21. The part 20^b may also be formed of sheet metal stamped into the form illustrated in the drawings in which it is shown as comprising side flanges 20^c united by a transverse web or flange 20^d. The 10 forward extensions of the side flanges 20^c are adapted to receive between them a pawl 22 and a detent 23. The pawl 22 is pivoted on a pin 24 which extends between the side flanges 20^c of the lever and the detent 23 is 15 mounted on the pin 21 which supports the lever. The upper hooked extremities 22^a and 23^a, respectively, of the pawl and the detent are adapted to engage the teeth 15^a of the rack bar and the arms 22^b and 23^b, respectively, of the pawl and detent, which extend below the axis of the lever are connected by a coil spring 25 having its arms or terminals 25^a connected to the pins 26 which are mounted on the arms 22^b and 23^b. 20 The detent 23 is provided with a laterally extending hub 23^c having mounted thereon another coil spring 27 which terminates in elongated arms 27^a and 27^b adapted to engage the lateral projections 22^d and 23^d which are formed on the hooked extremities of the pawl and detent. As shown in Figs. 3, 4 and 5, the arms of the spring 27 are free and have no appreciable effect upon the pawl or detent so that either of these members is 25 permitted by the spring 27 to pass out of engagement with the rack bar. However the hooked extremities 22^a and 23^a of the pawl and the detent may be maintained in engagement with the teeth of the rack bar by 30 operating a latch member 28 which is pivoted on one of the pins 14 previously described and which is provided with a transverse flange 28^a adapted to engage the upper arm 27^b of the spring 27 when the latch is 35 swung to the position illustrated in Fig. 1, thereby causing the arms 27^a and 27^b to engage the lateral projections 22^d and 23^d formed on the pawl and detent, respectively. The spring 27 is of greater strength than 40 the spring 25 so that when the latch 28 is in the position shown in Fig. 1, the effect of the spring 25 is overcome by the action of the spring 27. When the latch 28 is moved to the 45 position illustrated in Figs. 3 and 4, the spring 27 is disengaged from the pawl and the detent so that the spring 25 is then effective to bring about the necessary action of the pawl and the detent in permitting the lowering movement of the rack bar or 50 plunger. In order to maintain the pawl 22 in a position in alignment with the detent 23, a collar 29 is mounted on the pin 24 at one side of the pawl. In order to prevent the 55 excessive downward movement of the lever 20, a roller 30 is mounted on a pin 31 ex-

tending between the side walls 11^a at a point some distance below the axis 21 of the lever.

When it is desired to use the jack for lifting a body, the latch 28 is moved to the position illustrated in Fig. 1, thereby forcing the upper arm 27^b of the spring 27 into engagement with the upper end of the detent 23 and causing the other arm of the spring to move the pawl 22 into engagement with the rack bar. With the pawl and detent held in 70 engagement with the rack teeth by the arms of the spring 27, the reciprocation of the lever 20 about the axis 21 will cause the rack bar or plunger to be elevated by each upward movement of the pawl 22 and, after each upward movement of the rack bar, it is maintained in its elevated position by the detent 23, the hooked extremity 25^a of which slides over the inclined rack teeth during the 75 upward movement of the rack bar. When it is desired to lower the plunger or rack bar of the jack in its support, the latch bar 28 is moved to the position illustrated in Figs. 3 and 4 thereby disengaging the spring 27 from the detent 23 and causing it to have 80 no appreciable effect upon the pawl 22. When the lever is in its upper position as illustrated in Fig. 3, the pawl 22 is in the position illustrated by full lines in that figure and the detent 23 is in engagement with the 85 teeth of the rack bar, due to the fact that the downward movement of the pawl 22 causes the arms 25^a of the spring 25 to be compressed with a corresponding thrust on the arm 23^b of the detent and a consequent movement of 90 the upper end of the detent into engagement with the rack bar. As the lever 20 is lowered about its pivot 21, the arms 25^a of the spring 25 separate and the pawl 22 is rocked about its pivot 24 until it engages the teeth 95 of the rack bar and causes an upward movement of the rack bar sufficient to permit the disengagement of the detent 23 from the rack bar under the influence of the spring 25, it being understood that the arms 25^a of the 100 spring 25 are spread apart beyond their neutral or relaxed positions during the downward movements of the lever so that as the lever reaches the lower limit of its movement, the spring 25 exerts a pull on the lower arm 23^b of the detent which pulls the hooked extremity 23^a thereof out of engagement with the rack teeth. In this way the lever 20 105 may be reciprocated repeatedly until the rack bar 15 is lowered to the desired extent. When 110 there is no load on the jack, the rack bar may be conveniently lowered without reciprocating the lever by inserting a finger between the side walls 11^a and pressing inwardly on the arm 23^a of the detent until it releases the 115 rack bar.

In Fig. 7 there is illustrated a slight modification in which a pawl 22^x and a detent 23^x are mounted on pins engaging a lever 20^x, but the axis of the spring 27^x, instead of be-

ing coincident with the axis of the lever, is formed by a lug 33 on the detent above the member 21^k on which the lever is mounted.

Although I have shown and described one form of the invention, it will be understood that it may be constructed in various other embodiments without departing from the scope of the appended claims.

I claim:

1. A lifting jack comprising a rack, a pivotally mounted lever, an actuating pawl mounted to be actuated by said lever to move said rack bar, a holding detent pivotally mounted on said lever and adapted to engage said rack bar, a spring connecting said pawl and said detent to force them out of engagement with said rack to permit the lowering of said rack, and a second spring adapted to engage directly both said pawl and said detent to force them into engagement with said rack against the action of said first-named spring to permit the upward movement of said rack.

2. A lifting jack comprising a standard, a rack bar mounted for vertical movement in said standard, a lever pivotally mounted on said standard, a pawl pivoted on said lever and adapted to engage said rack bar, a detent pivoted on the axis of said pivotal mounting of said lever and adapted to engage said rack bar, said pawl and said detent having arms extending from their pivotal axes, opposite to the parts thereof which engage said rack bar, a coil spring having its extremities connected to the arms of said pawl and said detent, said spring being adapted to effect the alternate engagement and disengagement of said pawl and said detent with said rack bar to effect the lowering movement of said rack bar by the reciprocation of said lever, and a second spring of greater strength than said first named spring having parts adapted to engage said pawl and said detent above their pivotal axes to force the upper extremities of said pawl and said detent into engagement with said rack bar to effect the upward movement of said rack bar by the reciprocation of said lever.

3. A lifting jack comprising a standard, a rack bar mounted for vertical movement in said standard, a lever pivoted on said standard, an actuating pawl pivoted on said lever and adapted to actuate said rack bar upon movement of said lever, a holding detent mounted for pivotal movement about the pivotal axis of said lever and adapted to engage said rack bar, a spring carried entirely by and connecting said pawl and said detent at one side of their pivotal axes to control their engagement with said rack bar during the lowering movement of said rack bar by the reciprocation of said lever, and means comprising a second spring mounted to engage directly said pawl and said detent at the side of their pivotal axes opposite said first-named

spring for controlling the engagement of said pawl and said detent with said rack bar during the elevation of said rack bar by the reciprocation of said lever.

4. A lifting jack comprising a standard, a rack bar mounted for vertical movement in said standard, a lever pivotally mounted on said standard, a pawl pivoted on said lever and adapted to engage said rack bar, a detent pivoted on the axis of said pivotal mounting of said lever and adapted to engage said rack bar, said pawl and said detent having arms extending from their pivotal axes opposite the parts thereof which engage said rack bar, a coil spring having its extremities connected to the arms of said pawl and said detent, said spring being adapted to effect the alternate engagement and disengagement of said pawl and said detent with said rack bar to effect the lowering movement of said rack bar by a reciprocation of said lever, and a second spring of greater strength than said first named spring having parts adapted to engage said pawl and said detent above their pivotal axes to force the upper extremities of said pawl and said detent into engagement with said rack bar to effect the upward movement of said rack bar by the reciprocation of said lever, and means for rendering said second named spring inoperative when desired.

5. A lifting jack comprising a rack, a lever, an actuating pawl, a holding detent, said pawl and said detent being each pivotally mounted on said lever to permit movement thereof when said lever is actuated, said pawl and said detent having parts at one side of their pivotal axes adapted to engage said rack, a spring supported by and connecting said pawl and said detent at the side of their pivotal axes opposite said engaging parts for controlling the movement of said pawl and said detent during the lowering movement of said rack, and a second spring mounted independently of said first named spring and directly engaging said pawl and said detent adjacent said engaging parts for controlling the movements of said pawl and said detent during the elevation of said rack.

6. A lifting jack comprising a rack, a pivotally mounted lever, an actuating pawl pivoted on said lever to move said rack bar, a holding detent pivotally mounted for movement about the pivotal axis of said lever and adapted to engage said rack bar, a spring connecting said pawl and said detent to force them alternately out of engagement with said rack to permit the lowering of said rack, a second spring adapted to engage directly both said pawl and said detent to force them into engagement with said rack against the action of said first-named spring to permit the upward movement of said rack, and means for holding said last-named spring in engagement with said pawl and said detent.

7. A lifting jack comprising a standard a

rack bar mounted for vertical movement in said standard, a lever pivoted on said standard, an actuating pawl pivoted on said lever and adapted to engage said rack bar, a holding detent pivoted on a relatively stationary axis and adapted to engage said rack bar, a spring supported on and connecting the ends of said pawl and said detent at the side of their pivotal axes opposite their rack-engaging portions for controlling their engagement with said rack bar during the lowering movement of the rack bar by the reciprocation of said lever, a second spring mounted about the pivotal axis of said lever and having a pair of free extremities adapted to engage the rack-engaging portions of said pawl and said detent, respectively, and means for moving said free extremities of said last-named spring into and out of engagement with said pawl and said detent.
